United States Patent Office.

JOHN E. BLISS, OF OXFORD, INDIANA.

Letters Patent No. 71,960, dated December 10, 1867.

IMPROVEMENT IN BUILDERS' SCAFFOLD.

The Schedule referred to in these Letters Patent and making part of the same.

TO ALL WHOM IT MAY CONCERN:

Be it known that I, JOHN E. BLISS, of Oxford, in the county of Benton, and State of Indiana, have invented a new and improved Scaffold for Builders, &c.; and I do hereby declare that the following is a full, clear, and exact description thereof, which will enable others skilled in the art to make and use the same, reference being had to the accompanying drawings forming part of this specification.

Figure 1 is an end view of my improved scaffold when arranged for use.

Figure 2 is a front view of the same.

Similar letters of reference indicate corresponding parts.

My invention has for its object to furnish an improved scaffold, for the use of carpenters, masons, painters, &c., which shall be simple in construction, strong, durable, and easily adjusted to any desired height; and it consists in the combination of the right-angled pivoted frame and adjustable sliding bars with each other, as hereinafter more fully described.

A is a right-angled triangular frame, the arms a^1 and a^2 of which are securely framed to each other at one end, and their other ends are secured in place by the inclined braces a^3 . The frames A are still further strengthened at the angle by the triangular boards a^4 upon each side, between which is pivoted the upper end of the post or bar B, to the lower end of which is securely pivoted a link or band, C, which passes around the said lower end of the bar B, and around the bar D. The bar D has a link or band, E, rigidly attached to its upper end, which also passes around and slides up and down on the bar B, as shown in the drawings. The bar D has notches, d' , formed upon its side furthest from the bar B, into which the end bar of the link C may enter, and thus support the scaffold securely in any position in which it may be placed. This construction enables the scaffold to be easily adjusted to any desired height.

In using the apparatus, the extension-bars B and D are adjusted according to the height at which it is desired to have the platform or staging. The bars are then set in an inclined position, with one side of the right-angled frame A resting against the wall or frame of the building, and the planks or staging-boards F are placed upon the projecting horizontal side of said frame A. By this construction the greater part of the weight upon the scaffold will be sustained by the pressure of the vertical side of the frames A against the wall or frame of the building. The lower end of the bars D should be made pointed, and should be shod or plated with iron, so that it may enter the ground and be prevented from slipping.

I claim as new, and desire to secure by Letters Patent—

The combination of the right-angled pivoted frame A and adjustable sliding bars B and D with each other, substantially as herein shown and described, and for the purpose set forth.

JOHN E. BLISS.
